GOLF PUTTER HEAD

Emilio Miartuz, 237 Springs Ave., Miami Springs, Fla.

Filed June 11, 1963, Ser. No. 75,302

Term of patent 14 years

(Cl. D34—5)

FIG. 1 is a rear perspective view of a golf putter head embodying my new design;

FIG. 2 is a rear elevational view thereof;

FIG. 3 is a top plan view thereof;

FIG. 4 is a front elevational view thereof; and

FIG. 5 is a right end view of FIG. 2.

The essential features of my design reside in the portions shown in solid lines in the drawing, the broken lines shown on the rear face of the putter indicate a depression.

The broken line representation of a shaft portion is for illustrative purposes only.

I claim:

The ornamental design for a golf putter head, as shown and described.
